UNITED STATES PATENT OFFICE

2,059,586

COMBUSTION APPARATUS

Dwight F. Kilgour, Lexington, Mass.

Application September 9, 1931, Serial No. 561,872

3 Claims. (Cl. 110—86)

My invention relates to combustion apparatus, and more particularly, but not exclusively, to boiler settings having provision for burning oil, pulverized coal, and similar fuels.

5 This application is a continuation in part of application Serial Number 488,254, filed October 13, 1930 and renewed May 25, 1933, now Patent 1,924,209.

10 The invention will be best understood from the following description when read in the light of the accompanying drawing of one embodiment of the invention selected for illustrative purposes, the scope of the invention being more particularly pointed out in the appended claims.

15 In the drawing:—

Fig. 1 is a vertical section of a boiler setting with a fragment of the associated boiler; and

Fig. 2 is a section on the line 2—2 of Fig. 1, with parts shown in plan.

20 Referring to the drawing, the boiler setting illustrated has annular walls comprising the outer brickwork 4 and an inner structure 3 of refractory clay or fire-brick. As shown, the outer brickwork is formed to provide an arcuate chamber 5, and an upwardly extending wall 7 of reduced diameter upon the top of which rests the shell 9 of a boiler. The boiler, as illustrated, is of the fire-tube type, having the vertical fire-tubes 11 for ascending products of combustion, and the 25 return fire-tubes 13 for descending products of combustion, the latter discharging into a chamber 15 formed by the walls 7 and casing 17. As shown, the chamber 15 communicates with a 30 smoke-pipe 19 for leading the products of combustion to a stack.

35 As shown, the inner walls of the boiler setting are formed to provide a fire-pot having the cylindrical lateral walls 21 and the upwardly converging roof 23, the latter being provided with an axial circular opening 25 with which communicates an upwardly extending flue, the latter being circular in cross-section and having the upwardly and outwardly diverging walls 27.

40 In the present embodiment of the invention, the arcuate air chamber 5 extends almost completely around the fire-pot, and at one end thereof has an opening 29 communicating with the atmosphere, while at its other end it is provided with an opening 31 with which communicates the suction pipe 33 of a blower 35, the latter being driven by any suitable means as, for example, an electric motor 37. As shown, the discharge pipe of the blower communicates with the fire-pot 45 through an opening 41 arranged eccentrically of

the fire-pot. Interiorly of the pipe 39 is a nozzle 43 for fuel oil.

5 As a result of the above described construction, air is drawn through the opening 29 into the arcuate chamber 5 in which said air is heated, the hot air being discharged through the pipe 39 into the fire-pot, while oil is drawn from the nozzle 43 by ejector action and atomized and mixed with the hot air to form a combustible mixture. The ignited combustible mixture in the fire-pot is given a whirling motion due to the eccentric arrangement of the pipe 41, being held in the fire-pot for an appreciable time due to this motion and the restricted nature of the opening 25. Passing through the opening 25 the combustible mixture 10 enters the upwardly flaring flue 27, continuing its whirling motion, and rising slowly and expanding in the flue due to the increasing cross-sectional area of the latter. Due to this action the products of combustion are continuously intimately 15 mixed while combustion is taking place, with the result that the fuel is completely consumed. The products of combustion pass from the flue 27 into the fire-tubes 11 and then through the return tubes 13 to the chamber 15 and pipe 19. It has 20 been found that best results will be secured when the circular opening in the fire-pot roof is in the nature of a relatively sharp edge as shown in the application drawing. In practice however this edge need not be a "line" in the geometrical sense 25 of the word, but should not constitute an opening of material length axially thereof, because in such case the products of combustion would be directed by the opening axially of the diverging flue, which would prevent effective utilization of 30 the latter in respect to mixing the gases and securing complete combustion. It will be observed that the upwardly traveling whirling gas in the fire-pot adjacent the roof thereof is guided toward the opening 25 by the upwardly converging walls of said roof, which causes each particle 35 of the gas as it leaves the fire-pot to be directed upwardly and across the flue 27. For example, if the gaseous products in contact with the upwardly converging wall in the fire-pot roof 23 at the left 40 hand side of Fig. 1 are considered, when they reach the opening 25 they immediately travel over toward the right hand side of the upwardly diverging flue 27. As this occurs at all points around the circumference of the opening 25, spreading and intimate mixture of the gas take 45 place in the upwardly diverging flue 27 as soon as the gas enters it. If the opening 25 were of material length axially thereof, the whirling gases discharging from the opening into the upwardly 50

55

diverging flue 27 would be directed vertically upward and would not immediately spread, and as a consequence the effect of the flue 27 would be materially diminished in respect to securing complete combustion.

I have found that perfect combustion may be secured under favorable conditions by use of the throated, upwardly flaring flue provided by the central circular opening 25 in the roof of the fire-pot and the diverging walls 27, provided the flue is of sufficient length, which length for many installations would make the boiler setting of prohibitive height, especially where the boiler setting is used with a vertical boiler or other boiler having considerable height. I have found, however, that the length of this flue may be materially reduced without sacrifice of combustion efficiency by giving the products of combustion a whirling motion as they pass through the throat of the flue. As a result of this reduction in length of the flue, the height of the boiler setting may be materially reduced, making it practical to employ the throated flue in many situations where it would otherwise be impossible to do so, this reduction in height of the boiler setting having the further advantage that its construction involves less material and labor costs.

It will be understood that within the scope of the appended claims wide deviations may be made from the form of the invention herein described.

I claim:

1. Apparatus of the character described having, in combination, a fire-pot, a relatively long upwardly relatively slowly flaring flue of relatively large cross-sectional area for conducting combustion products from said fire-pot, and means for delivering mixed air and fuel to said fire-pot transversely and eccentrically thereof to cause a whirling of the combustion products therein about its axis prior to delivery to said flue,

said flaring flue communicating with said fire-pot through an opening formed in the fire-pot roof of sufficiently short length axially thereof to permit substantially immediate spreading of the whirling products of combustion as they enter said flue. 5

2. A furnace having, in combination, a fire-pot the roof of which is formed with a central opening, said fire-pot having substantially continuously transversely curved interior lateral walls, a flue having upwardly relatively slowly diverging 10 interior lateral walls of rounded cross-section in horizontal planes, which flue communicates with said central opening, and fuel nozzle means for delivering fuel to said fire-pot and directing it 15 against said interior lateral walls thereof at one side of the axis of the same for causing a whirling of combustion products therein prior to delivery to said opening, said central opening being of sufficiently short length axially thereof to permit 20 substantially immediate spreading of the whirling products of combustion as they enter said flue.

3. A furnace having, in combination, a fire-pot the roof of which has upwardly relatively quickly converging walls, said fire-pot having substantially continuously transversely curved interior lateral walls, a flue having upwardly relatively slowly diverging interior lateral walls communicating with said fire-pot through a central circular opening formed in said roof of relatively short 25 length axially thereof, said interior lateral walls of said fire-pot and flue being of circular cross-section in horizontal planes, and fuel nozzle means for delivering fuel to said fire-pot and directing it to impinge against said lateral interior walls thereof at one side of the axis of the same for causing a whirling of combustion products therein prior to delivery to said circular opening. 30
